US0D1042867S

(12) **United States Design Patent** (10) Patent No.: **US D1,042,867 S**
(45) Date of Patent: ** Sep. 17, 2024

(54) **HANDHELD MASSAGER**

(71) Applicant: **FKA Distributing Co., LLC**,
Commerce Township, MI (US)

(72) Inventors: **Kai Han**, Newmarket (CA); **Andrew Steven Juhasz**, Ajax (CA)

(73) Assignee: **FKA Distributing Co., LLC**,
Commerce Township, MI (US)

(**) Term: **15 Years**

(21) Appl. No.: **29/876,974**

(22) Filed: **May 31, 2023**
